PRESSURE SWITCH

Johan C. Albrecht, Garber, Okla.

Application July 18, 1935, Serial No. 32,126

4 Claims. (Cl. 200—81)

This invention relates to a drag extension for the pressure valve mechanism which operates an automatic switch to start and stop a pump for the supply of water, gas, oil, air or the like.

5 The invention aims to provide a constant drag on the operating parts, magnetically and in a novel and efficient manner, to prevent undue vibration of the switch operating mechanism, that is so hold the operating mechanism to take up 10 the variation in pressure of the water or fluid, especially in the stopping and starting of the motor, without unduly starting and stopping the motor, or failure to operate at all due to the rapidity of the variations in pressure in the fluid.

15 The more specific objects and advantages will become apparent from a consideration of the description following taken in connection with accompanying drawings illustrating an operative embodiment.

20 In said drawings:—

Figure 1 is a view illustrating the invention in connection with a pump in perspective;

Figure 2 is a perspective of the parts constituting the invention;

25 Figure 3 is a perspective view of the pressure valve; and

Figure 4 is a detail perspective view of the support for the switch operating rod.

Referring specifically to the drawings, 10 designates a switch box containing a switch adapted to be thrown into on and off positions through the operation of a lever 11 movable on a vertical axis. Such switch controls a periodically operating electric motor M adapted to pump water, gas, 15 oil, air or other fluid, and the pressure of which through a pipe 12 builds up in a chamber 13 to operate a plunger 14, which is urged closed by an expansive spring 15, and the tension of which is adjustable through the manipulation of a nut 16 threaded on the plunger, the plunger being 20 slidably mounted in a casing or mounting 17 to which the chamber or housing 13 is fastened as shown. The water or other fluid is adapted to be maintained in a tank T or the like in a pre- 25 determined quantity, and as such quantity diminishes to predetermined extent, the pressure on the plunger 14 is relieved so that means is set into motion to replenish the supply. Said plunger 14 has two laterally extending arms 18 fastened 30 thereto each provided with a vertical sleeve 19 at its outer end.

35 Removably disposed in one of the sleeves 19 is a crooked end 20 of a slidable switch operating rod 21. Such rod 21 is in sections 22 and 23, each of 40 which has a sleeve 24 adjustably fastened thereon

by a set screw 25, and to each of which sleeves a compression spring 26 is fastened. Said springs 26 in turn, are fastened to a short rod 27 secured to the switch arm 11. Said section 23 is slidably supported on a bracket 28 preferably of wood 45 secured for instance to the switch box 10.

Another rod 30, for instance, of copper has a bent terminal 31 removably disposed in the other sleeve 19 and at its other end is fastened to an iron bar 32 which is in contact with and slidable 10 along a horseshoe magnet 33. One or more of these magnets may be provided and they are fastened in place to a supporting base 34 as by means of a clamping bolt structure 35. The iron bar 32 is adapted to be attracted by the magnetism from the magnet or magnets 33 and since the rod 30 is of copper, the remaining parts are not subject to the magnetism to an extent sufficient to affect operation.

20 The casing 17 is preferably bolted or otherwise fastened as at 36 to the support 34, which latter may be of wood, for instance, and fastened to the water tank or the like adapted to be filled.

In the operation of the device, it will be clear 25 that as the water or other fluid diminishes from the tank, the pressure in the chamber 13 so operates the plunger 14 as to slide it, pulling the rod 21 and moving the switch 11 to the on position so that the pump operates to replenish the supply of fluid to the predetermined extent, after 30 which the rod 21 through the control of the plunger under pressure, moves in the opposite direction cutting off the motor. During the sliding movement of the plunger, the coaction 35 between the magnets 33 and iron bar 32 causes a continuous drag on the operation of the plunger and thus will hold the plunger and prevent its undue operation under variations of the pressure, especially taking up the variation or surge 40 of the water which is greatest at the stand-pipe or overhead tank at the stop and starting points of the motor, and which undue and unnecessary operation at the present time overheats the switch and its wire connections, often burning the fuses, and often being so fast that the motor 45 will neither start nor stop properly. The invention augments the action of the spring 15 which is not sufficient to control or regulate the back suction of the water, which is greatest when stopping or starting the motor.

50 Various changes may be resorted to provided they fall within the spirit and scope of the invention.

What is claimed is:—

1. In combination with a plunger to operate 55

electrical mechanism adapted to pump a fluid and through the pressure of which the plunger is controlled, a slidable rod connected to the plunger and magnetic means associated with the rod to exert a drag on the action of the plunger comprising an iron bar on the rod, and a horse-shoe magnet having both legs wiped by the bar.

2. In combination with a plunger to operate electrical mechanism adapted to pump a fluid and through the pressure of which the plunger is controlled, a slidable rod connected to the plunger, magnetic means associated with the rod to exert a drag on the action of the plunger comprising an iron bar on the rod, and a magnet slidably wiped by the bar, said rod having a depending terminal, an arm on the plunger engaged by said terminal, a second arm on said plunger, and a slidable switch operating rod connected to the second arm.

20 3. In combination with a plunger to operate electrical mechanism adapted to pump a fluid and through the pressure of which the plunger is controlled, a rod connected to the plunger, magnetic means associated with the rod to exert a drag on the action of the plunger comprising an iron bar on the rod, a magnet wiped by the bar,

said rod having a depending terminal, an arm on the plunger engaged by said terminal, a second arm on said plunger, a switch operating rod connected to the second arm, a box for the switch, resilient connections in the last mentioned rod connected to the switch, and a support port for the rod on the box.

4. In combination with a plunger to operate electrical mechanism adapted to pump a fluid and through the pressure of which the plunger is controlled, a rod connected to the plunger, magnetic means associated with the rod to exert a drag on the action of the plunger comprising an iron bar on the rod, a magnet wiped by the bar, said rod having a depending terminal, an arm on the plunger engaged by said terminal, a second arm on said plunger, a switch operating rod connected to the second arm, a box for the switch, resilient connections in the last mentioned rod connected to the switch, a support 20 for the rod on the box, a base supporting said magnet, a casing for the plunger on said base, and a pressure chamber associated with the plunger carried by the casing.
